Primary Examiner — Vy N Koenig*(74) Attorney, Agent, or Firm* — Seyfarth Shaw LLP;
Brian Michaelis(57) **CLAIM**

The ornamental design for the trigger stick assembly, as shown and described.

DESCRIPTION

FIG. 1 is a perspective view of a trigger stick assembly according to the present disclosure.

FIG. 2 is a detailed perspective view of the trigger stick assembly of FIG. 1.

FIG. 3 is a detailed left side view of the trigger stick assembly of FIG. 1.

FIG. 4 is a detailed right side view of the trigger stick assembly of FIG. 1.

FIG. 5 is a detailed rear view of the trigger stick assembly of FIG. 1.

FIG. 6 is a detailed front view of the trigger stick assembly of FIG. 1.

FIG. 7 is a detailed top view of the trigger stick assembly of FIG. 1.

FIG. 8 is a detailed bottom view of the trigger stick assembly of FIG. 1.

The features shown in broken lines in the drawings depict environmental subject matter and form no part of the claimed design.
